UNITED STATES PATENT OFFICE.

EDWARD M. COINTEPAS, OF BOSTON, ASSIGNOR, BY MESNE ASSIGNMENTS,
TO CHARLES H. WARD, OF CAMBRIDGE, MASSACHUSETTS.

GALVANIC BATTERY.

SPECIFICATION forming part of Letters Patent No. 269,179, dated December 19, 1882.

Application filed January 20, 1882. (No model.)

To all whom it may concern:

Be it known that I, EDWARD MARK COINTEPAS, a citizen of the Republic of France, residing at Boston, in the county of Suffolk and 5 State of Massachusetts, have invented certain new and useful Improvements in Galvanic Batteries; and I do hereby declare the following to be a full, clear, and exact description of the invention, such as will enable others 10 skilled in the art to which it appertains to make and use the same, reference being had to the accompanying drawings, and to letters or figures of reference marked thereon, which form a part of this specification.

15 This invention relates to galvanic batteries provided with attachments, and adapted to be used to produce a small incandescent light intended for domestic uses; and it consists, in combination with an acid-jar provided with 20 a removable cover; of the slab secured to the under side of said cover, and the carbon plates beveled at the top and secured to and depending from the under side of said slab, and a pole of the battery, which is attached to a boss 25 erected upon said slab, in the manner and for the purpose substantially as hereinafter set forth.

The drawings accompanying this specification represent in Figure 1 a perspective view, 30 and in Fig. 2 a cross-section, of a device embodying my invention. Fig. 3 is an isometric view of the carbon plates, and Fig. 4 a modified form of construction of the zinc plate.

35 A is the base supporting the jar or other vessel, B, the cover C of which is held in place by a hooked latch, a; or in any suitable manner by which it may be readily removed and applied.

40 The carbon plates, beveled at the top, are shown at E E as secured to and depending from the under side of a slab, F, which is composed of lead and antimony amalgamated, and is secured to the under side of the cover 45 C of the vessel B, and has a central opening, a', said carbon plates being immersed permanently in the exciting-liquid in the said jar.

The disk or block of zinc is shown at G, between the carbon plates E E, and preferably

has upon each side lateral spurs b b, of rubber 50 or other suitable non-conducting material, which constitute fenders to prevent contact of the zinc with the carbon. The zinc G is secured to and suspended from the lower end of a vertical rod or stem, H, which is guided 55 in vertical movements through the cover C by a tubular hub or sleeve, I, of india-rubber or other insulating material, inserted centrally in such cover, a button, e, being secured to the top of such stem H. The normal position 60 of the zinc G is above and out of contact with the exciting-liquid, and is suspended in this normal position by a wire, d, of brass or other suitable metal, which constitutes one of the poles of the battery, one end of this wire being secured to the top of the stem H, while its body is coiled about such stem and rests upon the top of the cover or the bearing-hub I, and thence joins one end of a coil, c', of 65 hard platinum wire disposed above the cover C. 70

The opposite pole of the apparatus is a copper tube, g, such tube at one end screwing into the top of a boss, h, erected upon and cast integral with the plate F of the carbons, and situated over one of said carbons. By 75 this manner of connecting the wire g' it is insulated from possibility of contact with the fumes of the exciting-liquid, and hence is protected from the corrosive influence of such fumes. The opposite end of the pole g connects with the opposite end of the platinum coil c'. The two poles d and g are thus insulated from each other, but are permanently connected by the platinum coil or spiral c'.

The operation of this apparatus is briefly 85 as follows: Depressing the knob e lowers the zinc G and immerses it in the exciting-liquid in the jar B, and an electric current is thereby established, the circuit being permanently closed by the union of the two poles d and g 90 through the medium of the platinum coil c', as before stated. The coil c' becomes heated to a white heat—in other words, rendered incandescent—and capable of igniting paper, wood, a jet of gas, the wick of a lamp, &c. 95

The rubber tube or cylinder interposed between the stem or suspensory H and the sleeve and spring surrounding it allows contact be-

tween said spring and rod only at the top, and thus compels the current to pass through the spring.

I claim—

5. In combination with the acid-jar B, provided with removable cover C, the slab F, secured to the under side of said cover, and the carbon plates E E, beveled at the top, and secured to and depending from the under side of said

slab, and pole g, which is attached to a boss ^{1c} erected upon said slab, in manner and for the purpose substantially as set forth.

In testimony whereof I affix my signature in presence of two witnesses.

EDWARD MARK COINTEPAS.
